UNITED STATES PATENT OFFICE

CLARENCE F. SHERIDAN, OF DETROIT, MICHIGAN

QUICK-CHANGE PUNCH AND HOLDER THEREFOR

Application filed May 31, 1928. Serial No. 281,703.

My invention relates to a new and useful improvement in a quick change punch and holder therefor, and has for its object the provision of a punch which may be easily and quickly removed from and replaced in the punch holder.

Another object of the invention is the provision of a means for retaining the punch which will permit easy and quick changing, and which may be economically manufactured, and which will be durable and efficient in use.

Other objects will appear hereinafter.

The invention consists in the combination and arrangement of parts hereinafter described and claimed.

The invention will be best understood by a reference to the accompanying drawings which form a part of this specification and in which,

Fig. 1 is a side elevational view of the invention with parts broken away and parts shown in section.

Fig. 2 is a view taken on line 2—2 of Fig. 1.

Fig. 3 is an enlarged view similar to Fig. 2, with the punch slightly turned.

The punch 7 is provided with a diametrically extending socket 8 adjacent its upper end and positioned in the socket 8 is a coil spring 9, engaging at one end the face of the socket and at the other end, a locking pin 10 which has a reduced stem 11 extending inwardly of the spring 9. The punch holder 12 is provided with a recess 13 communicating with the bore 14 into which the punch 7 is adapted to fit. This holder is secured by suitable screws 15 to a backing plate 16.

In use the punch 7 is inserted into the bore 14 and in order to accomplish this the locking pin 10 is thrust inwardly of the socket 8. When the punch 7 is thrust inwardly so as to engage the backing plate 16 a rotation of the punch 7 will bring the locking pin 10 into alignment with the recess 13, at which time the spring 9 will force the locking pin outwardly so as to engage in the recess 13 as shown in Figs. 1 and 2. By forming this recess 13 on the upper portion of the punch holder 12, the pin 10 serves to retain the

punch in the holder 12. One of the side walls 17 of the recess is formed tangent to the bore 14. Should the punch 7 become broken, damaged, or should it be desired for other reasons to remove the punch 7 from the holder 12, it would be but necessary to rotate the punch 7 so as to bring the end of the locking pin 10 into engagement with the tangential surface 17. A further rotation would effect an inward thrusting of the locking pin 10 until its outer end would lie flush with the periphery of the punch 7, at which time the punch 7 could be moved axially out of the socket 14.

In this way the mounting of the punch in the holder and its removal therefrom may be very easily and quickly effected.

While I have illustrated and described the preferred form of my invention, I do not wish to limit myself to the precise details of structure shown, but desire to avail myself of such variations and modifications as come within the scope of the appended claim.

Having thus described my invention what I claim as new and desire to secure by Letters Patent is:

A device of the class described, comprising: a punch holder having a bore formed therein and provided on its upper face with a recess communicating with said bore, one of the side walls of said recess being tangent to said bore and the other side wall being radial to said bore; a punch insertable into said bore; a radially movable locking member on said punch engageable in said recess for locking said punch against removal from said holder; and resilient means for normally thrusting said radially movable locking member outwardly beyond the periphery of said punch, into said recess, the rotation of said punch in said holder, effecting, through engagement of said locking member with said tangent side wall, an inward movement of said locking member to inoperative position.

In testimony whereof I have signed the foregoing specification.

CLARENCE F. SHERIDAN.
